[57] CLAIM

The ornamental design for a combined bag and handle, substantially as shown and described.

DESCRIPTION

FIG. 1 is a perspective view of a combined bag and handle showing my new design;

FIG. 2 is an elevational view thereof showing the side opposite that shown in FIG. 1;

FIG. 3 is an elevational view looking from the right of FIG. 2, the opposite side being a mirror image thereof;

FIG. 4 is a bottom plan view thereof; and

FIG. 5 is a top plan view thereof showing the top end in open configuration.
